(57) **CLAIM**

The ornamental design for an electrode array as shown and described.

DESCRIPTION

FIG. 1 is a perspective view of an electrode array in accordance with a first embodiment of our design;

FIG. 2 is a top plan view of the electrode array of FIG. 1; FIG. 3 is a bottom plan view of the electrode array of FIG. 1;

FIG. 4 is a right side elevational view of the electrode array of FIG. 1;

FIG. 5 is a left side elevational view of the electrode array of FIG. 1;

FIG. 6 is a rear elevational view of the electrode array of FIG. 1;

FIG. 7 is a front elevational view of the electrode array of FIG. 1;

FIG. 8 is a perspective view of an electrode array in accordance with a second embodiment of our design;

FIG. 9 is a top plan view of the electrode array of FIG. 8; FIG. 10 is a bottom plan view of the electrode array of FIG. 8;

FIG. 11 is a right side elevational view of the electrode array of FIG. 8;

FIG. 12 is a left side elevational view of the electrode array of FIG. 8;

FIG. 13 is a rear elevational view of the electrode array of FIG. 8;

(Continued)

FIG. 14 is a front elevational view of the electrode array of FIG. 8;

FIG. 15 is a perspective view of an electrode array in accordance with a third embodiment of our design;

FIG. 16 is a top plan view of the electrode array of FIG. 15;

FIG. 17 is a bottom plan view of the electrode array of FIG. 15;

FIG. 18 is a right side elevational view of the electrode array of FIG. 15;

FIG. 19 is a left side elevational view of the electrode array of FIG. 15;

FIG. 20 is a rear elevational view of the electrode array of FIG. 15;

FIG. 21 is a front elevational view of the electrode array of FIG. 15;

FIG. 22 is a perspective view of an electrode array in accordance with a fourth embodiment of our design;

FIG. 23 is a top plan view of the electrode array of FIG. 22;

FIG. 24 is a bottom plan view of the electrode array of FIG. 22;

FIG. 25 is a right side elevational view of the electrode array of FIG. 22;

FIG. 26 is a left side elevational view of the electrode array of FIG. 22;

FIG. 27 is a rear elevational view of the electrode array of FIG. 22; and,

FIG. 28 is a front elevational view of the electrode array of FIG. 22.

The broken lines having consistent dash lengths (dash-dash-dash) represent portions of the Medical Treatment Apparatus that form no part of the claimed design.

The broken lines having inconsistent dash lengths (short dash-medium dash-short dash) represent boundaries of the claimed design. As shown in FIGS. 8-10 and 22-24, the boundary lines are provided at an intersection between the

body of the electrode array and a port for an electrical connection.
